UNITED STATES PATENT OFFICE.

JOHN A. GIBB, OF NEW YORK, N. Y., ASSIGNOR TO PETROLEUM DERIVATIVES INCORPORATED, OF PORTLAND, MAINE, A CORPORATION OF MAINE.

CONDENSER.

Application filed May 7, 1927. Serial No. 189,508.

This invention relates to condensers and pertains more particularly to condensers which are especially adapted for use in fractional distillation processes such as the distillation of petroleum, for example.

It is an object of this invention to provide a condenser which shall be simple and inexpensive to construct. It is a further object of the invention to provide a condenser in which the condensed liquid is collected at a point sufficiently removed from the cooling surfaces of the condenser that the heat contained in the high boiling point constituents of the condensed liquid may be available to revaporize some of the low boiling constituents which have been condensed, whereby the flash point of the condensate may be improved.

Other objects and advantages of the invention will appear hereinafter.

A preferred embodiment of the invention selected for purposes of illustration is shown in the accompanying drawings, in which,

Figure 1 is a longitudinal sectional view.

Figure 2 is a section on the line 2—2 of Figure 1, and

Figure 3 is a transverse sectional view on the line 3—3 of Figure 1.

Referring to the drawings, the condenser comprises a casing 1 preferably substantially cylindrical, having an inlet port 2 and an outlet port 3 forming intake and discharge openings respectively for vapors which are to be condensed. Within the casing 1 is arranged a baffle plate 4 which is preferably secured to the internal walls of the condenser and extends from a point near the top of the casing to a point near the bottom thereof. The upper edge of the casing 1 is preferably provided with a flange 5 upon which may be seated a tube plate 6 carrying a plurality of substantially U-shaped cooling tubes 7, the said tubes being preferably arranged in banks located on either side of the baffle 4. For convenience one bank of tubes will be referred to as the A bank while the other bank of tubes will be referred to as the B bank.

Mounted above the tube plate 6 is a cover plate 8 having a pair of recesses 9 and 10 formed therein, the recess 9 communicating

with the inlet openings of all of the tubes 7 of both A and B banks, while the recess 10 communicates with the outlet openings of all the tubes 7 of both the A and B banks. Connected with the recess 9 is an intake conduit 11 and connected to the recess 10 is a discharge conduit 12 through which conduits the cooling medium may be led into the condenser and circulated through the tubes 7 and discharged from the condenser.

In order to secure the tube plate 6 and the cover 8 to the casing 1, the collar 13 may be provided through which the bolts 14 are passed, nuts 15 being provided to hold the tube plate in place and nuts 16 being provided to secure the cover plate. It will be observed that by reason of this arrangement it is possible to remove the cover from the condenser (if this is desirable for any reason such as to blow out the tubes, for example) without interfering with the flow of vapors through the condenser, and without breaking the vacuum in the system if the condenser is used in connection with a vacuum distillation process. Furthermore, if several condensers of the type illustrated are connected in series, one or more may be cut out of the system at any time simply by cutting off the flow of cooling medium, and the vapors then pass through to the next unit.

The bottom of the casing 1 is closed by the plate 18 which carries the well 19 in which is located one end of the overflow pipe 20, the said pipe passing through the side of the casing through the opening 21 at a point located above the level of the bottom of the condenser, but below the level of the cooling tubes 7.

When the apparatus is in operation vapors are introduced through the intake conduit and are deflected upwardly by the baffle 4 to secure contact thereof with the A bank of cooling tubes. As the vapors reach the top of the condenser they pass over the top of the baffle plate and are deflected downwardly along the B bank of tubes. Any uncondensed vapors are discharged from the condenser through the port 3.

It will be observed that the level of the

discharge pipe 20 is such as to cause a pool of oil to form at the bottom of the condenser and in the well 19, the well 19 serving as a sediment collector to remove from the discharge pipe 20 any dirt or foreign matter which may find its way into the condenser. It will also be observed that the surface of the said pool of oil is sufficiently removed from the cooling tubes so that the cooling effect of the said tubes thereon is negligible. Accordingly, the said pool of oil is hot and is continually receiving additional quantities of hot distillate from the sections of the condenser above. The high boiling point constituents which are condensed are at a temperature sufficiently in excess of the boiling points of some of the lower boiling point constituents so that the said high boiling point constituents provide the latent heat necessary to cause some of the said low boiling point constituents to be revaporized, whereupon the vapors pass into the vapor stream and eventually pass out of the condenser. It will also be observed that the cooling tubes 7 may expand and contract freely and without constraint under the influence of changes in temperature.

If, for any reason, the pipe 20 becomes blocked up so that condensate cannot pass therethrough, the liquid level rises until it reaches the port 3, and the condensate then overflows into the next succeeding unit. The operation of the condenser is not affected in such event, however, for vapors may still pass through the condenser as before.

If desired, a heating coil (not shown) may be located in the bottom of the condenser to supply additional heat to assist in the revaporization of the low boiling point constituents.

It will be understood that the invention may be variously modified and embodied within the scope of the subjoined claims.

I claim as my invention:

1. In a condenser having vapor inlet and discharge ports, a cooling surface, means to cause a pool of condensate to be collected in said condenser, said cooling surface being out of contact with said pool of condensate, said inlet and discharge ports being located in close proximity to said pool, whereby the heat from vapors passing through said condenser may revaporize low boiling point constituents of the condensate.

2. In a condenser having vapor inlet and discharge ports, a cooling surface, means to cause a pool of condensate to be collected in said condenser, said cooling surface being out of contact with said pool of condensate, said inlet and discharge ports being located to permit the heat from vapors passing through said condenser to revaporize low boiling point constituents of the condensate.

65 In testimony whereof, I have signed my

name to this specification this 6th day of May, 1927.

JOHN A. GIBB.
